UNITED STATES PATENT OFFICE

JOHN P. WEIS, OF NYACK, NEW YORK, ASSIGNOR TO METROPOLITAN SEWING MACHINE CORPORATION, OF NYACK, NEW YORK, A CORPORATION OF DELAWARE

METHOD OF MAKING MULTIPLE SEAMS

Original application filed November 13, 1928, Serial No. 319,072. Divided and this application filed July 12, 1929. Serial No. 377,682.

This invention relates to an improved method of making multiple seams, with a single handling of the work by the operator, in various articles of manufacture, such as 5 shoes, sporting goods, articles made from leather, canvas and other materials, and other wearing apparel requiring a strong, flat seam, the present improved method being particularly adapted for the sewing of 10 tapered shoe uppers or quarters, the present application being a division of my contemporaneously pending application, Serial No. 319,072, filed November 13, 1928.

A further object of the invention is the 15 provision of an improved method for first stitching the superposed parts or plies of the article with a single line of stitches, subsequently opening and flattening the seam, and stitching to the so flattened seam a reinforcing tape in an expeditious manner by parallel lines of stitches, with one handling of the article by the operator.

Another object of the invention is the provision of an improved method which may be 25 readily carried out by the provision of a plurality of stitching and feeding mechanisms arranged in tandem relation whereby the work is conveyed from one to the other automatically for the production of sewed articles having a seam composed of two separate and distinct characteristics whereby the superposed parts of the article may be first 30 stitched together and flattened out and subsequently stitched to complete the same.

Another object of the invention is the provision of an improved method readily performed by stitching mechanisms so organized that, simultaneously with the stitching of the first seam, the margins of the top and 35 bottom plies of the seam will be diverted in opposite directions initially to open the seam and during the guiding thereof to a second mechanism, and simultaneously with such movement from one mechanism to the other, a portion of the work will be overturned in 40 readiness to receive one or more lines of stitching in the final stitching operation for the formation of a taped, flat seam.

In the drawings accompanying and forming 45 a part of this specification—

Figure 1 is a front end view of a machine adapted to carry out this improved method illustrating the stitching mechanism for sewing the superposed plies of material, the means for overturning one ply of the work 55 and flattening the seam, the means for applying a tape to the flattened seam, and the stitching mechanism for stitching the flattened seam and tape with parallel rows of stitches;

Fig. 2 is a rear end view of the machine shown mounted upon a power-table;

Fig. 3 is a partly cross-sectional view of this improved machine taken on line 3—3, Fig. 2, and illustrates a front view of the interposed puller feed mechanism;

Fig. 4 is a top plan view of Fig. 1;

Fig. 5 is a perspective view of the operating connections of the feeding and stitching mechanisms of the machine;

Fig. 6 shows the two plies or pieces of work sewn together with a plain seam or single line of stitches;

Fig. 7 shows the two pieces of work with the seam margins spread in opposite directions and illustrates the first step in the seam opening and flattening process;

Fig. 8 shows the third step in the process where the top ply of the work is being overturned or flopped over;

Fig. 9 shows the top ply of the work overturned still further;

Fig. 10 shows the work with the top ply all the way over;

Fig. 11 shows the work completely flattened out;

Fig. 12 shows the work with the tape stitched to the flattened-out seam by two parallel lines of stitches;

Fig. 13 is a perspective view illustrating 90 how the two plies of work are separated during the first stitching operation by means of suitable guiding members projecting between the pieces of work;

Fig. 14 illustrates the seam flattened by 95 the pressure rolls of the puller feed mechanism;

Fig. 15 is a sectional view of a portion of the seam guiding and controlling means for acting upon the flattened seam as it passes 100

from the feed rolls to the tape stitching mechanism;

Fig. 16 is a detail, partly sectional, view showing the initial seam flattening means 5 and the separating members for overturning one ply of the work;

Fig. 17 is an enlarged plan view of the parts shown in Fig. 16;

Fig. 18 is a perspective view of the initial 10 seam flattening means for effecting the first flattening of the seam during the first stitching operation;

Fig. 19 is a perspective view of the throat-plate and feed dog of the tape stitching mechanism;

Fig. 20 is a detail, cross-sectional view taken on line 20—20, Fig. 1, looking in the direction of the arrows; and

Fig. 21 is a detail view illustrating three 20 shoe uppers in which the two plies of the upper A are stitched together by a single line of stitches and the seam then flattened, as illustrated by the upper B, and then covered by a tape applied and stitched by two lines of 25 stitching, as illustrated by the upper C,—the said uppers being united by a single line of stitches, whereby the feeding through the machine is facilitated.

Similar characters of reference indicate 30 corresponding parts in the several views.

Before explaining in detail the present improvement and mode of operation thereof, I desire to have it understood that the invention is not limited to the details of construction and arrangement of parts which 35 are illustrated in the accompanying drawings, since the invention is capable of other embodiments, and that the phraseology which I employ is for the purpose of description and not of limitation.

In practice I have preferred to make use 40 of a power table equipment such as shown in Figs. 2 and 3, for instance, upon which the machine is mounted, although this is not 45 essential. Such a power-table, however, will facilitate the handling of the work by a single operator and offers advantages by reason of the fact that the various units or mechanisms making up the machine can be 50 located to advantage in the factories where they are used so that the inspection of the work coming from the machine may be taken care of by a single person engaged in the examination of the product delivered from 55 these stitching units, which is not so readily accomplished if the stitching units are erected on ordinary sewing tables.

This power-table consists of two pairs of 60 connected supporting legs 1 and 2, connected by a brace or cross-member 3, which support a table top 4 upon which the machine is mounted for operation. An electric motor 5 is suitably mounted under the table top and is connected to a clutch 6 of any well-known type. This clutch is under the control

of an arm 7 of a bell-crank lever pivoted at 8 to the cross-member 3. The other arm 9 has connected to it an adjustable rod 10, the lower end of which is connected to a treadle 11. This treadle is pivotally supported on a brace rod 12 also connected to the legs 1 and 2. By manipulating the treadle the clutch 6 of the electric motor 5 starts or stops the operation of the belt wheel 13 carried on the end of the clutch shaft 14 and carrying the sewing machine drive belt 15 which operates the belt wheel 16 to give power to the sewing mechanism, generally indicated by 17, for stitching the two plies of the work, in the form of machine shown, by a single line of stitches.

This sewing mechanism 17 is equipped with suitable stitching and feeding mechanism. While I have shown a sewing mechanism of the well-known "metropolitan" rotary construction, the invention is not limited thereto, for any other type of sewing mechanism can be used for this purpose. However, in addition to the usual mechanisms employed for ordinary stitching, it is necessary to use additional mechanisms to accomplish the desired result, which consist of special means for separating, guiding and controlling portions of the work, so that instead of an ordinary seam being made by the sewing mechanism, a special form of seam is produced, delivered therefrom with the margins of the seam opened up flat for subsequent operations.

The sewing mechanism 17 is secured to the 100 table by bolts 18 and is provided with a bottom shaft 19 (see, for instance, Fig. 5) and a top shaft 20 for operating the needle bar 21 carrying a needle 77. Co-operating with the needle 77 is a thread carrying looper 77a. 105 The top shaft carries a sprocket wheel 22 for a chain 23 which operates a similar sprocket 24 carried on a shaft 25 of the second sewing mechanism, generally indicated by 26. This second sewing mechanism 26 has a 110 needle bar 27 carrying a pair of needles 145 operated by the shaft 25 and which also has a bottom shaft 28 provided with a hand wheel 29 for convenience in turning the sewing mechanism by hand. Co-operating with the pair of needles 145 is a pair of loopers 145a, each carrying a thread. The sewing mechanism 26 is also secured to the table by bolts 30 and may also be of the well-known "metropolitan" rotary construction, but instead of being equipped with a single needle and looper like the first sewing mechanism 17, it is provided, as stated, with two needles and two loopers for making two separated parallel rows of stitches for the purpose of 115 stitching a tape 31.

The needle bars 21 and 27 are operated by the usual crank 146 and pitman connections 147. To transmit rotary motion from the shaft 19 to the shaft 20 in the sewing mech- 120 130

anism 17, three-throw crank shafts and connecting rods 148 are provided, while to transmit motion from the shaft 25 to the shaft 28 similar crank shafts and connections 149 5 are provided.

The four-motion feed mechanisms of both sewing mechanisms comprise an adjustable crank 150 operating a link connection 151 and a feed rocker frame 152 carrying the 0 usual feed bar 153 and feed dog 154. The feed dog 154 of the sewing mechanism 26, however, is shaped to suit the feeding of the tape 31 and to accommodate the two needles for making the two lines of stitches.

5 Thus each of the sewing mechanisms above referred to is provided with suitable feeding mechanisms for feeding the work and with suitable looper and needle operating mechanisms.

0 The tape 31 is carried by the reel 32 supported by a hanger 33 attached to the bottom of the table top 4 (Fig. 2). This tape feeds upward through the table top into a guide 34 carried by the sewing mechanism 26, from 5 which it is guided into proper stitching position.

In co-operative relation with the sewing mechanisms 17 and 26 is a puller feed mechanism which assists in feeding, guiding and flattening the work as it passes from the first to the second sewing mechanism. This puller feed mechanism (see Fig. 3) is also secured to the table top by bolts 35 passing through the frame 36 thereof which is provided with bearings 37 and 38 in which operates a shaft 39. On one end of this shaft is secured a feed operating wheel 40. Adjacent to this wheel is a reciprocating ratchet member or lever 41 carrying one or more feed 10 pawls for intermittent gripping action on the feed wheel 40. A collar 42 holds the parts in operative position. A back-lash pawl or member 43 controls the movement of the feed wheel 40 in one direction. This pawl 15 is adjustably held in place by a fixed crank arm 44. Connected to the lever 41, at 45 (see Figs. 1, 2 and 5), is a rod 46, the other end of which is connected to a crank pin 48 carried by the belt wheel 16 which thus gives 20 movement to the rod 46, whereby intermittent movement is given to the puller feed shaft 39 and the feed roll 49 secured thereto.

This feed roll 49 co-operates with an upper feed roll 50 revolving on a shaft 51 carried 25 by a yoked bracket 52. This yoked bracket is secured to a presser bar 53 operating in bearings 54 for up and down movement. Attached to this presser bar is a lifting collar 55 which co-operates with 30 the curved forked end 56 of a lifting lever 57 pivotally secured to the frame, as at 58. This part of the puller feed frame is in the form of an overhanging arm 60 terminating in the two bearings 54. A lug 61, formed as 35 a part of the overhanging arm, provides a

support for a presser spring 62, the other end of which rests on the collar 55, thus giving a downward pressure to the roller 50 which thus acts as a pressing roll for flattening the seam simultaneously with the feeding of the 70 work.

To regulate the pressure on this spring 62, a screw 63 is provided tapped into a lug 64 of the overhanging arm 60. In order to lift the top roller 50, the lever 57 has an extending end 65 to which is connected a chain 66 reaching down to one arm 67 of a rock shaft 68 carried by bearings 69. The other arm 70 (see Fig. 5) has connected to it another chain 71 extending downward and connected to a foot treadle 72 which is also pivotally supported on the rod 12 side by side with the treadle 11 (see Fig. 3). Pressure on this treadle 72 operates through the chains and the lever 65, pivoted to 75 58, to lift the roller 50 from the roller 49. 85

If it be desired, for any reason whatever, to hold the feed roll 50 in an elevated position, as shown in Fig. 1, a swinging latch 55a is provided and is pivoted to the collar 55 at 55b and can be swung into contact with the casting at 55c and thus hold the roller up. This swinging latch is provided with a knob or handle 55d for convenience in swinging it into and out of operative position by hand. 95

The ply overturning or flopping means 74 is secured to the bearings 54 of the puller feed mechanism at 73—73 (see Figs. 2 and 3) and is shown formed of sheet metal, and extends downward and outward toward the sewing mechanism 17. This member 74 (see Figs. 2 and 4) has a right-angled bent portion 75, the edge 80 of which forms a guide, for the purpose hereinafter set forth, and a curved vertical edge 76 (see Figs. 1 and 2), and this curved vertical edge 76 extends into position opposite the needle 77 of the sewing mechanism 17. The member 74 terminates at 78 in a pointed member 79 (see Figs. 4, 13, 16 and 17) which extends backward and laterally to form the right-angled bent portion 75 having the guiding edge 80 hereinbefore referred to (Fig. 17). This right-angled bent portion 75 (see Fig. 4) is toward the rear of this member 74 increased in width, as at 81, so as to form a flared portion 82 to act upon the seam in the manner hereinafter described. This overturning member 74 has its point 79 projecting in between the plies of material as it is fed through the machine and thus separates one ply from the other and gradually effects the overturning or reversal of one portion or ply of the material being stitched as this ply is fed up the vertical inclined edge 76 of the member 74. 100 110 115

Attached to the cloth-plate 83 of the sewing mechanism 17 is a guide 84 (see Fig. 17) adjustably secured thereto by screws 85 and provided with an elevating screw 86 tapped 120 125 130

into the guide shank 87, whereby the guide can be adjusted up and down and the projecting end 88 thereof, which is secured to the shank by a screw 89, can be adjusted vertically. 5 This projecting end 88 extends across the path of the feed of the work to be stitched and is spaced above the cloth-plate, so that one ply feeds underneath while the other ply feeds over the top thereof (see Fig. 13). 10 The adjusting screw 86 permits the vertical shifting of the guide so that the proper space is provided underneath the same for the free passage of the work between it and the top surface of the cloth-plate. The 15 guide is provided with an upstanding lip 90 for guiding the work and regulating the margin thereof from the stitch line to the edge and so control the width of the seam. The 20 guide 84—87 for controlling and separating the work is so located relatively to the stitching position as to effectively control the work as if feeds through the first sewing mechanism, while at the same time it will not interfere with the ease of placing the articles 25 to be stitched in position, so that the feed and foot will immediately take hold of the work and feed same through the sewing mechanism.

It is, therefore, important to have the parts 30 arranged, as shown, relatively to the needle. Adjustably secured to this guide 84, by a screw 92, is an extending portion 91 having a part 93 in position to engage a seam-flattening member 94 (see Fig. 17) carried by a stem 35 95 secured in a holder 96 pivoted at 97 to a bracket 98 secured to the cloth-plate by screws 99. A spring 100 attached to the bracket 98 has its end exerting pressure against the holder 96 so as to hold it against 40 the work as it is fed through to flatten the seam, as shown in Fig. 16, with one edge 101 turned upward and the other edge 102 turned downward. The object of the spring 100 is not only to exert pressure so as to flatten the 45 seam, but also to yield so as to accommodate different thicknesses of material.

The presser foot 103, with a laterally-extending shank 104 and an upturned end 105, is carried by the presser bar 106 operating 50 in the bearing 107 of the machine head 108. A guide 109 (see Fig. 1) prevents the bar from turning in its bearing, and a hand lifter 110 is used for lifting the presser foot, a presser spring being provided to give pressure to the foot. For lifting the presser foot 55 by a knee shift or otherwise, a hook and lever, generally indicated by 112, may be used, either or both of which may be connected by chains with the pedal 72 whereby they may 60 be simultaneously lifted with the presser feed roller.

The foregoing description of the presser foot mechanism of sewing mechanism 17 will also suffice for sewing mechanism 26.

65 The presser foot 103 is provided with a nee-

dle hole 113 and a curved edge 114 to permit the edges of the work, as it is being stitched, to turn outward and downward so that the flared portions of the seam will pass through the narrow channel indicated at 115 (Fig. 16). 70

Now, viewing Figs. 6 to 11, inclusive, it will be seen that the needle 77 passing through the needle holder 113 of the presser foot 103 forms the seam 116 of Fig. 6. Immediately after the first stitches are made, the edges 101 75 and 102 are forced upward and downward to the position shown in Figs. 7 and 8; then, as the work proceeds, the top ply rides up the incline 76, which causes it to turn over, as indicated by 117 (Fig. 9); and then, as the work 80 proceeds further, this top ply is laid over, as indicated by 118 in Fig. 10. As the work progresses to this position, the edges 101 and 102 gradually turn under so as to flatten out to position shown in Fig. 11, while the seam 85 is guided and drawn through by the chain of stitches 119 (see Fig. 21). As the work is fed through, the seam has a tendency to resume its initial condition, as shown in Fig. 6, and before it enters the guiding members 90 about to be described it thus has a tendency to spring back into a condition such as illustrated in Fig. 20, wherein the bottom ply is indicated by 121 and the top ply is indicated by 120 and which top ply has been turned 95 over. To prevent this, a curved guard 122 (see also Fig. 4) limits and controls the top 100 ply 120, while a crotch-shaped guide member 123 rests upon the outside or open portion of the seam of the work. This member has a shank 124 secured to a bracket arm 125 (see Figs. 1 and 20) carried by the turn-over member 74, being attached thereto by screws 126. This crotch-shaped member 123 is adjustable 105 vertically to suit different kinds of seams and materials. The marginal edges of the seam contact with a curved member 127 (see Fig. 20) attached to the underside of a bent-up 110 guide plate 128 carried by a right-angled bracket 129 secured to the frame of the puller feed mechanism (see Figs. 1 and 20). This right-angled bracket 129 also carries another bent-up guide 130, thus forming a space or trough between them for the passage of the 115 seam, as indicated at 131 (Fig. 20). When the work reaches this point, however, it is fed and drawn along by the chain of stitches 119 (Fig. 21) by reason of the pull of the feed rolls 49 and 50 of the puller feed mechanism, the work having been guided from the 120 first stitching mechanism by suitable guides, comprising the edge 80 of the overturning member 74 and an overhanging edge of a companion guide 132 (see Fig. 4), both of which, at their front ends, are located adjacent to the 125 first sewing mechanism—the guide 132, however, being somewhat in the rear of the front end of the overturning member 74. These guides thus receive the seam from the sewing mechanism in an approximately flattened 130

condition by reason of the first spreading and flattening means 94—the ply, however, having been partially turned over when it reaches the opposed guide edges 80 and 132 by means of which the seam is, as stated, properly guided to the crotch-shaped member 123 and so prevented from returning to its initial condition. The guide edge of the guide 132 is cut at an angle, as at 133, and extends under the overhanging part 134 which is a continuation of one portion of the crotch-shaped member 123, the other part thereof being the oppositely-extending member or plate 137 (see Figs. 4 and 20). A top guide member 135, shown formed as a part of the crotch shank 124 (see Figs. 1 and 4), has a curved forward end 136 extending over the right-angled portion 75 of the turn-over member 74 and acts against the work as it feeds through after being turned over to force the seam down underneath the laterally-extending curved edges 81 and 82 (see Fig. 4) of the guiding means, whereby it is led to the crotch-shaped member 123. Thus, when the seam reaches the crotch-shaped member 123, it is confined between the guide plates 128 and 130 (Fig. 20) and so passes directly under the crotch-shaped member 123 comprising the angularly-extending plates 134 and 137. These members or plates 134 and 137 extend back toward the lower feed roll 49 and an extending lip 138 (see Figs. 1 and 4) of the top guide 135 reaches out from the rear of such top guiding member 135, which, as stated, is a continuation of the shank portion 124 of the crotch-shaped member 123, and so maintains the seam in proper position for passage to the feed rolls. By reason of these several guiding members, the seam is controlled and fed directly to the feed rolls 49 and 50, where it is further flattened (see Fig. 14) and fed to the rear stitching mechanism 26. From the feed rolls of the puller feed mechanism the seam of the work passes through a trough-shaped guide formed by a guide member 141 comprising a bent-up plate attached by screws to a shank 139, which shank is attached to the frame of the puller feed mechanism by screws 140, and which guide member 141 forms a guide at one side, while a similarly bent-up plate 142, attached by screws, forms a guide for the opposite side of the seam. These guides are substantially the same as the guide plates 128 and 130 so far as the control of the seam is concerned. Duplicates of these guide-plates, as 141' and 142', are also attached to the slide plate 143 of the sewing mechanism 26. This slide plate fits into the cloth-plate 144 and is held in place by a simple spring clip, affording a quick means for the removal and replacement of the plate for convenience in threading the loopers. The seam passes through the two sets of guide plates just described to the needles 145 of the sewing mechanism 26, which needles are suitably spaced

(see Fig. 5) to make two parallel rows of stitches, one along each side of the junction of the flattened seam, so as to place two rows of stitching through the plies of work 120 and 121 and through each portion 101 and 102 of the flattened seam and also through the marginal edges of the reinforcing tape 31 (see Fig. 12).

As the work feeds out from the final stitching operation, the seam is thus completed with three stitch lines, as shown, 116 and 145b, and forms a taped seam adapted for use with shoes and other articles of wearing apparel, as well as for sporting goods articles made from leather, canvas and other materials requiring a strong, flat seam.

The operation of the machine is as follows: Upon operating the foot treadle 11 the clutch 6 is thrown into operation and thereupon the motor 5 drives the belt wheel 16 of the first sewing mechanism by the drive belt 15. Simultaneously therewith the rear sewing mechanism 26 is started by the chain 23 connecting the two sewing mechanisms, and at the same time the puller feed mechanism is started by the rod 46 connected with the operating means of the first sewing mechanism. The operator thereupon places the two plies of work (in this instance, a pair of shoe quarters or uppers) in position on the cloth-plate 83, one ply on top of the other, with the projection 88 of the ply separating means 84 and the forward or separating end 79 of the ply turn-over member 74 between the plies (Fig. 13). The two superposed plies are then fed through the first stitching mechanism of the machine, making the stitch line 116 (Fig. 6). As the marginal edges of the seam which extend to the right of this stitch line project into the path of the seam flattening member 94 (Fig. 16, for instance), one edge is diverted upward and the other downward and somewhat flattened. Space is required for the free movement of the diverted edges, and to accommodate the downward bent edge 102 of the work I provide a clearance cut 102a (Fig. 17) in the cloth-path 83 in the rear of the stitching mechanism. As the first sewed article emerges from the sewing mechanism 17, the top ply of the work 120 feeds up the inclined edge 76 of the turn-over member 74 until the work has passed from between the feed and presser foot of the sewing mechanism 17. Then another article is started in the same manner as the first one just described. After the first article has passed the sewing mechanism 17 and while the second article is being stitched, it is necessary to assist the feeding of the first article until the feed rolls of the puller feed mechanism can act upon it to feed it through to the second sewing mechanism 26, unless the length of the first article be sufficient to reach from the feeding mechanism of the first sewing mechanism to the feed rolls of the puller feed mecha-

- nism. From then on, however, the feeding of the work continues automatically, it being merely necessary for the operator to place the two plies of work into position on the cloth-plate 83 in the manner just described to be sewed by the first stitching mechanism. The puller feed mechanism forces the stitched article along until it is gripped by the feeding mechanism of the second sewing mechanism 26 for the final stitching operation thereon. In Figs. 4 and 21 it will be seen that there are two articles representing portions of shoes, such as shoe quarters, illustrated by the broken dotted lines as the top plies 120—15 one in position to receive the final stitching of the tape to the seam, the next in the process of having the seams pressed down between the rollers of the puller feed mechanism, and the next just passing beyond the 20 stitching position of the sewing mechanism 17.

To facilitate the feeding of the separate articles from one mechanism to the other, the connected chain of stitches 119 is utilized 25 (Fig. 21), this chain of stitches running from one article to another as the stitching proceeds, there being sufficient strength to the chain of stitches joining the articles to enable the sewing mechanism 26 to do the entire 30 feeding of the work; but, to insure a more positive feeding of the work and also to flatten the seam, the feed rolls of the puller feed mechanism also assist in such feeding, and to facilitate the starting of the work at the 35 beginning of the stitching operation the feeding mechanism of the sewing mechanism 17 is employed.

From the foregoing it will be understood 40 that when the sewing mechanism 17 is placed in operation, the puller feed mechanism and also the sewing mechanism 26 are likewise operated in the manner hereinbefore explained, the movements of which are timed in relation to one another through the 45 connections hereinbefore described, so that the needles and feeding movement are timed in relation to one another to effect the proper working of the several mechanisms of the machine.

50 While I have shown three mechanisms in the group forming this improved machine, two of which have stitching mechanisms, it is to be understood that the invention is not thus limited, for it is obvious that other 55 stitching mechanisms can be operated in a similar manner to effect a series of different operations by the one handling or passing of the work through the group.

It is also to be understood that while the 60 drawings and description show rotary and four-motion feeding mechanisms grouped in a particular manner to suit the operation on the work described, with the puller feed mechanism in between the two sewing mechanisms so as to permit this puller feed mecha-

nism to act as a puller and a pusher in the feeding of the work, yet for some kinds of work it may be desirable to have the puller feed mechanism in the rear of the sewing mechanism 26 so as to pull the work through 70 both sewing mechanisms.

In the present improved machine the arrangement of the feeding mechanisms and the operation thereof provide independent 75 adjustments for the stroke of each feeding device, which permits the use of a slightly longer stroke on any of the feeds as may be desired, according to the character of the work the machine is operating on. By adjusting the crank pins 150 (see Fig. 5) of the two sewing mechanisms, the feed stroke may be regulated. By adjusting the crank 48 (see Figs. 1 and 2), the stroke of the puller feed is regulated. Moreover, since each of the 80 three mechanisms has an independent pressure by the medium of presser foot or presser roller acting on top of the work, different degrees of pressure can be had, not only for pressing the seams but also to effect a change 85 or regulation as a means of control for the feeding.

The cross-sectional view of the work in Fig. 12 shows two lines of stitching 145b made by the needles 145 of the sewing mechanism 26. The illustration is exaggerated to 90 more clearly illustrate the seam structure by reason of the slight space shown between the marginal edges 101 and 102 and the plies 120 and 121, whereas in practice these parts are so flattened out and drawn together by the 95 stitches that there is no space whatever between the two. Thus it will be seen that the row of stitches 116 extends transversely to the parallel rows of stitches 145b; that is to say, the 100 first stitch line at first is at right angles to the plane of the work (Fig. 16), but in the completed article (Fig. 12) it is parallel to the plane of the work, while the two parallel 105 lines of stitches are always at right angles to the plane of the work (Fig. 12) and, therefore, transverse to the row of stitches 116.

Fig. 21 illustrates three articles representing shoe quarters, the first having the seam A partly flattened out and illustrates the seam 110 as it emerges from the first sewing mechanism 17, while the seam B illustrates the work as it is passing through the puller mechanism where the seam is completely flattened, while the part C shows the completed seam with the tape 31 stitched in place by the two lines 115 of stitches 145b.

Since the work produced by the machine shown and described may be frequently in the form of separate articles stitched together, such articles being small portions of shoes or other similar articles, they are delivered from the machine connected by means of the tape 31 as well as a chain of stitches 119. It is, therefore, necessary that these parts be 120 separated. This operation, in some instances,

can best be accomplished by an attendant who inspects the work as the pieces are cut apart while in other instances it may be desirable to employ a mechanically-operated 5 shears or severing device located just behind the presser foot of the sewing mechanism 26, so that as each article feeds through the knife or shear will separate one from the other.

A brace bar preferably connects the over- 10 hanging arms of the sewing mechanism 17 and puller feed mechanism.

It is to be understood that by describing in detail herein any particular form, structure or arrangement, it is not intended to 15 limit the invention beyond the terms of the several claims or the requirements of the prior art.

Having thus explained the nature of my 20 said invention and described a way of constructing and using the same, although without attempting to set forth all of the forms in which it may be made or all of the modes of its use, I claim:

1. The method of stitching articles with 25 multiple seams which consists of stitching two superposed plies of material, then while the lower ply is maintained in substantially the same plane during the sequence of operations, overturning the top ply thereof into 30 reversed position with the inside outside, and then stitching the seam margins with parallel rows of stitches.

2. The method of stitching articles with 35 multiple seams which consists of stitching two superposed plies of material, then spreading and flattening the seam margins thereof, then while the lower ply is maintained in substantially the same plane during the sequence of operations, overturning the 40 top ply of the work into a reversed position with the inside outside, and then stitching the flattened seam margins with parallel rows of stitches.

3. The method of stitching articles with 45 multiple seams which consists of stitching two superposed plies of material, then spreading and flattening the seam margins thereof in opposite directions, then while the lower ply is maintained in substantially the same 50 plane during the sequence of operations, overturning the top ply of the work into a reversed position with the inside outside, then while holding the seam margins so spread applying a stay strip to the flattened seam, 55 and then stitching such stay strip to the flattened seam with parallel rows of stitches.

4. The method of stitching articles with 60 multiple seams which consists of stitching two superposed plies of material with a single row of stitches, then spreading the seam margins in opposite directions and flattening the same, then guiding the seam margins and preventing the return thereof to their original position and during such guiding over- 65 turning one ply of the work, then further

flattening the previously-flattened seam margins and feeding them into position to receive parallel rows of stitches, then applying a stay strip to the flattened seam, and then stitching the stay strip thereto with parallel rows of stitches whereby the parallel rows of stitches will be laid transversely to the single row of stitches.

5. The method of stitching articles with 70 multiple seams which consists of stitching two superposed plies of material with a single row of stitches, then spreading the seam margins and holding, guiding and feeding them into position to be flattened, then flattening them in parallelism with the plies of material, and then stitching to the so flattened seam margins a stay strip with parallel rows 75 of stitches.

6. The method of sewing articles with 80 multiple seams which consists of utilizing the 85 stitches uniting a plurality of articles to feed such articles and simultaneously stitching superposed plies of one of said articles while overturning a ply, guiding and flattening the seam with the seam margins spread in opposite directions of another of said articles, and sewing the so flattened seam of another of said articles with parallel rows of stitches.

7. The method of sewing articles with 90 multiple seams which consists of utilizing the 95 stitches uniting a plurality of articles to feed such articles and simultaneously stitching superposed plies of one of said articles while overturning a ply, guiding and flattening the seam with the seam margins spread in opposite directions of another of said articles, applying a stay strip to another of said articles, and then sewing the same to the flattened seam thereof with parallel rows of 100 stitches.

8. The method of sewing articles with 105 multiple seams which consists of presenting the work to be stitched in a flat condition and stitching the same, then shifting the seam margins into a vertical position substantially at right angles to the body of the work, then shifting the seam margins into a substantially horizontal position in parallelism with the body of the work but spaced therefrom, then pressing the seam margins and the work 110 together to eliminate space therebetween, and then stitching the seam margins to the body of the work.

9. The method of sewing articles with 115 multiple seams which consists of presenting the work to be stitched in a flat condition and stitching the same, then shifting the seam margins into a vertical position substantially at right angles to the body of the work, then shifting the seam margins into a substantially horizontal position in parallelism with the body of the work but spaced therefrom, then pressing the seam margins and the work 120 together to eliminate space therebetween, and then supplying a covering tape to the 125 130

seam margins and stitching the same to the work.

10. The method of stitching articles with multiple seams which consists of stitching two superposed plies of material, then while the lower ply is maintained in substantially the same plane during the sequence of operations automatically overturning the top ply thereof into a reversed position with the ⁵ side outside, and then stitching the seam margins with parallel rows of stitches.

11. The method of stitching articles with multiple seams which consists of stitching two superposed plies of material, then automatically spreading and flattening the seam margins thereof, then while the lower ply is maintained in substantially the same plane during the sequence of operations automatically overturning the top ply of the work ¹⁵ into a reversed position with the inside outside, and then stitching the flattened seam margins with parallel rows of stitches.

12. The method of stitching articles with multiple seams which consists of stitching two superposed plies of material, then automatically spreading and flattening the seam margins thereof in opposite directions, then while the lower ply is maintained in substantially the same plane during the sequence of ²⁵ operations, automatically overturning the top ply of the work into a reversed position with the inside outside, then while holding the seam margins so spread automatically applying a stay strip to the flattened seam, ³⁰ and then stitching such stay strip to the flattened seam with parallel rows of stitches.

Signed at Nyack, New York, this 27th day of June, 1929.

JOHN P. WEIS.
